CLAIM

The ornamental design for a power distribution unit, as shown and described.

DESCRIPTION

FIG. 1 is a top perspective view of a power distribution unit showing my new design;

FIG. 2 is an enlarge view as shown in FIG. 1;

FIG. 3 is an enlarge view as shown in FIG. 1;

FIG. 4 is a bottom perspective view thereof;

FIG. 5 is an enlarge view as shown in FIG. 4;

FIG. 6 is a front elevational view of FIG. 1;

FIG. 7 is a rear elevational view of FIG. 1;

FIG. 8 is a left side elevational view of FIG. 1;

FIG. 9 is a right side elevational view of FIG. 1;

FIG. 10 is a top plan view of FIG. 1; and,

FIG. 11 is a bottom plan view of FIG. 1.

The broken lines of the drawings represent portions of the power distribution unit that forms not part of the claimed design.
